(57) **CLAIM**

The ornamental design for rubber mop, as shown and described.

DESCRIPTION

FIG. 1 is a bottom view of a rubber mop in accordance with the new design;

FIG. 2 is a front view thereof;

FIG. 3 is a top view thereof;

FIG. 4 is a right side view thereof;

FIG. 5 is a bottom perspective thereof; and,

FIG. 6 is a top perspective view thereof.

The broken lines illustrate portions of the rubber mop that form no part of the claimed design.
